4 Claims. (Cl. 307—88.5)

The invention concerns a trigger circuit where triggering occurs in dependence on a control voltage which acts at least for a short time and exceeds a minimum value.

According to the invention the control voltage is transmitted to the control electrode circuit of a transistor, and an interrupting contact and the switching element provided for utilizing the impulses are located in the collector electrode circuit of the transistor, a resistor being located in the common lead of both circuits in series with the base electrode.

The invention is now explained by means of the circuit diagrams shown in the drawing, Figs. 2 and 3 being modified arrangements of the basic circuit shown in Fig. 1.

In Fig. 1 reference numeral 1 indicates the block-shaped semi-conductor of the transistor, for instance a germanium plate, 2 is the base electrode, 3 the control electrode and 4 the collector electrode. In the control electrode circuit is a bias voltage source 5, for instance a battery, and the input circuit element 7 for introducing the control voltage, for instance the secondary winding of a transformer. The circuit of the collector electrode 4 contains a source of D. C. potential 6 and the output circuit element 8 for utilizing the triggering impulses, for instance the coil of a relay, as well as the interrupting contact 10. Both circuits are connected by means of the common resistor 9 to the base electrode 2. When a control voltage occurs at element 7, such voltage being of a polarity which, in effect, increases, i. e. adds to the voltage of the bias voltage source 5, a current will flow through control electrode 3 to base electrode 2, whereby a relatively large change in current strength occurs in the circuit of the collector electrode due to the amplification effect of the transistor. This increase in current strength becomes noticeable at resistor 9 where a higher potential drop occurs which adds itself to the control voltage. There will thus be an increase in amplification, that is to say a feed-back to the control circuit. The feed-back increases with the magnitude of the resistance 9. If the resistance continues to be increased a point will be reached where the amplification process changes over to a triggering process. The increased current which flows over the collector electrode may in some cases continue to flow, even when the control voltage has ceased. In order to stop this current, contact 10 has to be opened for a short time, whereupon the original condition is restored. Triggering is thus to a great extent dependent on the magnitude of resistor 9.

Triggering can be improved when rectifiers are provided in the control circuit as indicated in Fig. 2. For this purpose an asymmetrically conducting device such as for example a rectifier 11 is connected in series with the transformer which transmits the control voltage. The method of operation is as follows: When a control voltage occurs at element 7, during the positive half wave thereof a current will flow over rectifier 11 so as to increase the polarization voltage at electrode 3. The function of rectifier 11 is to effect a substantial reduction in the reactive effect on the input circuit after the triggering action is completed, the rectifier serving as a block for the reactive voltage

2

which occurs at such time. Increase in polarization voltage at electrode 3 results in a triggering current in the collector electrode circuit which at resistor 9 has the effect of a feed-back to the control circuit. In the control circuit there is an increase of current over the control electrode 3. This current rise produces an effect over rectifier 12, whereby switch element 7 remains unloaded. Rectifier 12 or an equivalent asymmetrically conducting device is connected in series with the circuit which includes battery 5, control electrode 3 and resistor 9 and is so poled, as shown on the drawing, that in the absence of any input voltage pulse appearing on transformer secondary 7, a very low amplitude current will flow in this circuit. The voltage in element 7 may be of very short duration, but even then the feedback current over rectifier 12 will continue to flow. This expedient has a favourable effect on the initiation of the current rise and also helps to maintain it.

The introduction of the control voltage into the control circuit can of course also occur at any other point in the circuit in an electrically equivalent manner. Due to the coupling of the circuits, any voltage which is introduced will always have an effect on the control circuit so that triggering is started, although there will be a diminution in power amplification. The improvement in the effect of the rectifier is thus also maintained. A point for the introduction of the voltage is for instance at the resistor 9. The input voltage can then become effective either in series or in parallel with the resistor. Such an arrangement is shown in Fig. 3. The network 17 in which the control voltage occurs is connected in series with a rectifier 11 and across the feed-back resistor 9. Resistor 9 also has a rectifier 13 arranged in series with it. This rectifier 13 prevents the control voltage which acts on the resistor 9 from being short circuited over load resistor 8, battery 6 and the transistor. During its effective phase the polarity of the control voltage is opposed to that of battery 6. If the voltage of the battery 6 predominates, a voltage occurs at electrode 4 which would act in the forward direction of the transistor and cause a short circuit. No triggering could occur in this case. As in the case of the Fig. 2 circuit, rectifier 11, in series between transformer secondary 17, to which the triggering impulse or control voltage is applied, and resistor 9, serves to reduce any reactive effect on the input circuit element 17 following the triggering action of the transistor circuit. Rectifier 13, corresponding in function to rectifier 12 in the Fig. 2 circuit, is placed in series in the circuit which includes the collector electrode 4, battery 6, output element 8, switch 10, resistor 9 and base electrode 2, and is so poled, as indicated on the drawing, that a very low amplitude current flows through this circuit in the absence of a triggering voltage impulse at transformer secondary 17.

In order to improve the triggering of the circuit still further, it can be an advantage to arrange separate bias voltages in series with the individual rectifiers.

Instead of the rectifiers or the resistors it is also possible to use voltage-dependent resistances, for example silit rods or the like, silit being the trade name for a material made by exposing mixed silicon, silicon carbide, and carbon, to the action of carbon monoxide at 1500° C.

The advantage of this circuit compared with a trigger circuit employing electronic tubes is that the life of the transistor is practically unlimited. The circuit is thus particularly suitable where trigger circuits are required in connection with supervisory devices for electrical plants. A very useful application of the circuit is for impedance protective devices where short impulses have to produce a tripping effect with absolute certainty.

I claim:

1. In a control circuit, the combination comprising a transistor having a control electrode, a collector electrode

and a base electrode, a first transistor circuit including said control electrode, a source of bias potential and said base electrode, a second transistor circuit including said collector and base electrodes, a resistor connected in a lead common to both of said transistor circuits in series with said base electrode to promote feedback from said second transistor circuit to said first transistor circuit, an input circuit including an input element therein by which a triggering voltage can be introduced, said input circuit including a first asymmetrical conducting device in series with said input element, means connecting said input circuit with one of said transistor circuits, and a second asymmetrical conducting device connected in one of said transistor circuits poled to establish a low resistance path for flow of positive emitter and base electrode current, said first asymmetrical conducting device being poled to establish a low resistance path therethrough for current flowing through said input element and a high resistance path through said second asymmetrical conducting device.

2. A control circuit as defined in claim 1 wherein said second asymmetrical conducting device is connected in said first transistor circuit, and said series connected input

element and first asymmetrical conducting device constituting said input circuit are connected in parallel with said second asymmetrical conducting device.

5 3. A control circuit as defined in claim 1 wherein said series connected input element and first asymmetrical conducting device constituting said input circuit are connected in parallel with said resistor.

10 4. A control circuit as defined in claim 3 wherein said second asymmetrical conducting device is connected in said lead common to both of said transistor circuits.
